UNITED STATES PATENT OFFICE.

OSCAR WIEDERHOLD, OF EAST ORANGE, NEW JERSEY.

GAS-BURNER.

SPECIFICATION forming part of Letters Patent No. 658,099, dated September 18, 1900.

Application filed November 13, 1899. Serial No. 736,773. (No model.)

To all whom it may concern:

Be it known that I, OSCAR WIEDERHOLD, a citizen of the United States, residing in East Orange, Essex county, New Jersey, have invented certain new and useful Improvements in Gas-Burners, of which the following is a specification.

My invention relates to burners especially adapted for use with incandescent gas-lamps and will be described with reference to the accompanying drawings, which show a lamp in which my invention is embodied. The drawings, however, are illustrative merely of one form in which my invention may be clothed.

In the drawings, Figure 1 is a vertical transverse section of the lamp; Fig. 2, a horizontal section on the line 2 2 of Fig. 1, showing also the line 1 1, upon which the section of Fig. 1 is taken. Fig. 3 is a detail sectional view of the inlet-cock, the section being taken on the line 3 3 of Fig. 1. Fig. 4 is a plan view of the base-plug casing which forms a support for the burner; and Fig. 5 is a section on the line 5 5 of Fig. 1, showing the relations of the parts of the gas-regulator. Fig. 6 is a fragmentary sectional view of the upper end of the burner, the section being taken at right angles to the section-line 1 1 of Fig. 2, upon which the section Fig. 1 is taken.

In the drawings, *a* is a suitable nipple or base-plug casing having a conical passage therein for the reception of the rotary gas-controlling cock or plug *b*. An externally-threaded hollow plug-casing *c* projects from the base-plug and is pierced laterally to form apertures *d* for the passage of gas. The plug *c* terminates in a conical obstruction *c'*, which is adapted to enter the aperture *c''* in a thin plate *c''*, which is spun into place in the internally-threaded sleeve *c''*, which works upon the threaded plug *c*, being operated by the handle *c''*. The casing *e* is supported by the base-plug casing and is shown as apertured at *e'* for the passage of the handle *c''* of the movable sleeve *c''*. By rotating the movable sleeve it will ride on the screw-threads, and thus will be raised or lowered, so that the obstruction *c'* will enter the aperture *c''* to a greater or less extent, whereby the flow of the gas through the said aperture will be regulated. The plate *c''* is so thin that it will not

reduce the gas-pressure, which would occur if the said plate were thick. This plate is preferably of the thickness of one one-hundredth of an inch. The casing *e* is pierced laterally with air-passages *e''*, through which the air is drawn by the inrush of gas. *f* is a mixing-chamber located above the gas-inlet *e''* and is suitably supported in place, preferably, by the flanged ring *f'*, which is seated in the casing *e* at a suitable height, so as to form below it an annular chamber *g* between the casing *e* and the mixing-chamber *f*. The mixing-chamber *f* is laterally apertured at or near its upper end with apertures *f''* and is closed at the upper end by a spreader. This spreader is shown as of a generally-dished shape, having the bottom *h* provided with the upwardly-extending ring *h'*, the laterally-extending flange *h''*, and the upwardly-flaring ring *h''*.

A foraminous casing *i* surrounds the upper end of the mixing-chamber and is located between the said mixing-chamber and the casing *e*, being held in place at the top by the flaring ring *h''*, by which its upper end is closed, and at the bottom by means of a ring *e''*, secured in the casing *e*, by which its lower end is closed, so that the air and gas mixture which is drawn into the mixing-chamber *f* will escape laterally therefrom through the apertures *f''*, will thence envelop the mixing-chamber, thereby becoming heated, will pass through the foraminous casing throughout its entire extent, (dependent upon the pressure,) and will be delivered to the burning-point of the burner around the flaring edge *h''* of the spreader.

A by-pass tube *j* is seated in the base-plug *a* and communicates with the axial passage *a'* thereof by a slot in the tapered plug *b* when the tapered plug is swung into one of its positions where the flow of gas to the main burner is cut off. This by-pass may be controlled by a suitable screw-valve *a''*. The by-pass tube extends upward along the outside of the mixing-chamber and passes through one of the lateral orifices or apertures therein and extending through the spreader in the middle of the burner terminates at about the burning-point of the said burner. A burner constructed as shown in the drawings is especially adapted for heating the

mantle, as, owing to the construction thereof and especially to the presence of the foraminous casing, the gas will be very thoroughly and efficiently mixed with air and the Bunsen flame will be annular and very intense.

Having described my invention, what I claim, and desire to secure by Letters Patent, is—

1. In a burner, the combination of a mixing-chamber having lateral gas-delivering openings at or near its upper end and a foraminous casing surrounding the said mixing-chamber and extending below the said openings and a spreader located above the openings of the mixing-chamber, substantially as described and for the purposes set forth.

2. In a burner, the combination of a tubular mixing-chamber closed at its upper end and provided with lateral gas-delivering openings and a foraminous casing surrounding the said mixing-chamber and extending below the said openings.

3. In a burner, the combination of a mixing-chamber provided with lateral gas-delivering openings, a foraminous casing surrounding the said mixing-chamber and forming an annular chamber with the wall of the said mixing-chamber, substantially as described.

4. In a burner, the combination of a mixing-chamber closed at its upper end and provided with lateral gas-delivering openings and a foraminous casing surrounding the

said mixing-chamber and extending above and below the said openings.

5. In a burner, the combination of a mixing-chamber closed at its upper end and provided with lateral openings and a foraminous casing surrounding the said mixing-chamber at such a distance therefrom as to form with the said mixing-chamber an open space for the more thorough commingling of the air and gas mixture, the said foraminous casing being closed at its upper and lower portions, whereby the gas and air mixture will be projected laterally from the mixing-chamber into a space where the air and gas will be thoroughly commingled and pass out laterally through the interstices of the foraminous casing.

6. In an incandescent gas-burner, the combination of a mixing-chamber provided with lateral openings at or near the top thereof, a foraminous casing surrounding the said mixing-chamber at a sufficient distance therefrom to form an annular chamber in which the air and gas mixture can be more thoroughly commingled, the said foraminous casing being closed at its top and bottom, substantially as described and for the purposes set forth.

OSCAR WIEDERHOLD.
